[57] CLAIM

The ornamental design for a dental console, substantially as shown and described.

DESCRIPTION

FIG. 1 is a front perspective view taken generally from one side of the dental console showing my new design; FIG. 2 is a front elevational view of the dental console of FIG. 1;

FIG. 3 is a side elevational view of one side of the dental console of FIG. 1;

FIG. 4 is a front perspective view taken generally from the other side of the dental console of FIG. 1;

FIG. 5 is a top plan view of the dental console of FIGS. 1 and 4; and

FIG. 6 is a side elevational view of the other side of the dental console of FIG. 4.
